and 61 define arcs of a circle and have been provided with female threads 64.

First and second dies 66 and 67 are provided in each of the slots 46 through 50. These dies correspond quite closely in their configurations to the shape of the slots 46, 48 and 50. These first and second dies have mating faces 70 and are slidably movable in the slots. Each of the dies has outwardly curved or off-set portions 72 and 73, respectively, which are adapted to interfit with the corresponding portions in the die holding slots. Each of the mating faces of the dies is provided with a half round groove 75 which extends from one end portion 76 thereof to the other end portion 77 where it meets with a diverging opening 78. The dies 66 and 67 which are utilized in the die holding slots 47 and 49 are of a shorter length than the axial length of these slots so that the position of the dies within these two slots may be axially adjusted. The position of the dies within the slots is adjustable and they are held in a fixed position by means of first and second clamping screws 80 and 81, respectively. These clamping screws are provided with male threads on the outer periphery thereof and they reside in the slots at either end and contact the surface of the dies at the sides opposite the mating faces and hold the dies in a fixed position. Wall means are also provided in the arbor which define a plurality of axially spaced apertures 83 which extend completely through the arbor. These apertures extend generally normal to the die holding slots as well as transverse to the axis 34.

In operation, depending upon the type of wire or stock which is to be straightened, the dies 66 and 67 are placed in their respective holding slots, for example, in the manner illustrated in FIGURES 2 and 4. In this position it will be noted that the dies within the adjustment slots 47 and 49 are located in the closest positions to the center die holding slot 48. This would produce the greatest bending of the stock of which the straightening apparatus is capable. Although the dies can be located in varying positions in their respective die holding slots, it will be noted that the opening which is formed by the grooves in the mating faces of the dies in slots 46 and 50 lie on the axis 34. The opening in the dies in slot 47 lies below the axis, in slot 48 above the axis and in slot 49, again below the axis. The position of this opening with respect to the axis and the axial positioning of the dies within the adjustment slots 47 and 49 determines the severity of the bend to which the stock is subjected. After the dies have been positioned, a wire 85 is threaded through the arbor by way of the opening 40 in the left end portion 37 through all of the dies as indicated thereafter exiting the arbor through the right end portion 38 thereof. The wire is then threaded through the feed roll 22 and then on to the cut-off assembly 23 shown in the machine of FIGURE 1. The motive power source is then actuated and the wire 85 is drawn through the arbor and the arbor is caused to rotate on the bearing means 43 and 44 at a comparatively high speed relative to the longitudinal travel of the wire. In apparatus such as that disclosed in the instant application a range of arbors may be designed to handle wire sizes from $\frac{1}{32}$ inch to $1\frac{1}{4}$ inches in outside diameter. For the sake of example, and not of limitation, the apparatus illustrated in FIGURES 1 through 8 is designed to handle wire in the range of from $\frac{1}{16}$ inch to $\frac{5}{16}$ inch. In this instance the rotational speed of the arbor might be approximately 4700 revolutions per minute and the linear speed of the wire through the arbor might be in the range of from 65 to 200 feet per minute. To handle wire at one end of this range the dies might be located as shown in FIGURE 2 whereas if wire at the other end of the range is to be handled the dies might be moved to the position shown in FIGURE 3. This is accomplished by removing the clamping screws 80 and 81 and withdrawing the dies 66 and 67 and moving them axially to the posi-

tion farthest from the center die holding slot 48. The same procedure is followed in re-threading the wire through the arbor and between the feed rolls.

In the design of other arbors to handle another range of wire sizes for example wire in the range of from $\frac{1}{2}$ inch to $\frac{3}{4}$ inch, the rotational speed of the arbor might be in the neighborhood of 1740 revolutions per minute while maintaining a linear wire feed of from 75 feet per minute to 135 feet per minute. It should also be readily appreciated by those skilled in the art that each arbor might be associated with a variable speed mechanism whereby it may be driven at many rotational speeds from the motive power source. Although for the sake of example a range of wire sizes and arbor characteristics have been given, it will be easily recognized that the principles herein disclosed might be applied to other ranges and stock sizes without departing from the instant teachings.

FIGURES 9 through 13 illustrate a modification of the invention shown in FIGURES 1 through 8. FIGURES 9 and 10 illustrate an arbor 90 having an axial extending opening 91 therethrough and also provided with five die holding slots, the same as in FIGURES 4 and 5, indicated by the reference numerals 94 through 98. Die holding slots 95 and 97 which are alternate slots may also be referred to as adjusting slots. The adjusting slots 95 and 97 are of greater length than the other three slots for a purpose to be hereinafter explained. Each of the slots is provided with an outwardly curved or off-set portion 101 and 102, respectively. It will be noted that each of the slots is provided with only first and second curved portions 101 and 102 which are centrally located within the slot. The dies which have been described hereinabove, namely, the dies shown in FIGURES 6, 7 and 8 are adapted to slidably fit within the die holding slots 94, 96 and 98, however, a new type of die is designed for the adjusting slots 95 and 97. This die has been indicated generally by the reference numeral 105 and has first and second end portions 106 and 107, respectively. Each of the first and second end portions of the die 105 are provided with outwardly diverging openings 110 between which is provided a half round groove 111 in the mating face of the die. Each of the dies is provided with first and second curved or off-set portions 113 and 114 which are unsymmetrically located with respect to the end portions of the die. The positions in which the dies 105 have been shown in FIGURES 9 and 10 serve to locate the end portions 106 closest the central slot 96 and thus effectively reduce the distance between the center or produce a sharper bend between the center slot and the adjusting slots. If it is desirable that the bend at this place be less severe then it is only necessary to withdraw the dies 105 from the adjusting slots 95 and 97 and reverse the positions in which they are shown in FIGURES 9 and 10. This effectively accomplishes substantially the same end which is accomplished by the structure in the arbor shown and illustrated in FIGURES 4 and 5.

It will thus be seen that stock straightening apparatus has been provided which is capable of handling a wider range of stock from the standpoint of size as well as to the physical characteristics than that which is capable of being handled by a similar prior art device. This is accomplished by providing the means for adjusting not only the position of the dies in a direction transverse to the axis of the rotatable arbor, but also axially with respect to the arbor. This, in effect, varies the severity or the degree of bend to which the stock is subjected. The longitudinal movement of the arbor in combination with the rotational or axial movement of the wire therethrough in effect bends the wire an infinite number of directions about each linear position of the wire.

Although this invention has been described in its preferred form with a certain degree of particularity, it is understood that the present disclosure of the preferred

form has been made only by way of example and that numerous changes in the details of construction and the combination and arrangement of parts may be resorted to without departing from the spirit and the scope of the invention as hereinafter claimed.

What is claimed is:

1. Wire straightening apparatus comprising in combination an arbor rotatable about a substantially horizontal axis, said arbor having first and second end portions, wall means defining an opening extending axially through said arbor, bearing means mounting said first and second end portions of said arbor, a plurality of die holding slots extending through said arbor generally transverse to said axis, each of said slots including first and second opposed walls, said first and second opposed walls of each of said slots each having an outwardly curved portion defining an arc of a circle, every other of said slots being longer in an axial direction than the remaining slots, female threads on said outwardly curved portions, first and second dies having mating faces and slidably residing in each of said die holding slots, each of said dies having first and second end portions and curved portions to interfit said curved portions of said slots, said first end portion of each said die residing in each of said every other slot being longer than said second end portion thereof thereby making each said die unsymmetrical with respect to said curved portions, each of said mating faces having a half-round groove extending between diverging openings at either end portion thereof, first and second clamping screws having male threads thereon and residing in either end of each said slot with the male threads engaging the female threads on said outwardly curved portions, each said first and second clamping screws engaging each said first and second dies, respectively, to locate the same in each said slot, wall means defining a plurality of axially spaced viewing apertures extending through said arbor and said viewing apertures extending generally normal to said slots and intersecting a portion of a slot.

2. Wire straightening apparatus comprising in combination an arbor rotatable about an axis, said arbor having first and second end portions, wall means defining an opening extending axially through said arbor, bearing means mounting said first and second end portions of said arbor, a plurality of die holding slots extending through said arbor generally transverse to said axis, each of said

5

slots including first and second opposed walls, said first and second opposed walls of each of said slots each having an outwardly off-set portion, every other of said slots being longer in an axial direction than the remaining slots, first and second dies having mating faces and slidably residing in each of said die holding slots, each of said dies having first and second end portions and off-set portions to interfit said off-set portions of said slots, said first end portion of each said die residing in each of said every other slot being longer than said second end portion thereof thereby making each said die unsymmetrical with respect to said off-set portions, each of said mating faces having a groove extending between diverging openings at either end portion thereof, holding means in either end portion of each said slot and engaging each said first and second dies, respectively, to locate same in each said slot, wall means defining a plurality of axially spaced viewing apertures extending through said arbor, said viewing apertures extending generally normal to said slots and intersecting a portion of a slot.

3. Wire straightening apparatus comprising in combination a rotatable arbor, said arbor including an adjusting die holding slot extending transversely into said arbor, said slot including opposed walls and first and second ends, said opposed walls each having an off-set portion, first and second dies having mating faces and slidably residing in said die holding slot, each of said dies having first and second end portions and off-set portions to interfit said off-set portions of said slot walls, said first end portion of said dies being longer than said second end portion thereby making said dies unsymmetrical with respect to said off-set portions, said first end portion of said dies being located adjacent said first end of said slot and said second end portion of said dies being spaced from said second end of said slot and upon reversal of said dies in said slot said first end portion of said dies being located adjacent said second end of said slot and said second end portion of said dies being spaced from said first end of said slot, said mating faces defining an opening through said dies, and holding means locating said dies in said slot.
